UNITED STATES PATENT OFFICE.

GAETANO IMPELLITTERI AND ANTONINO IMPELLITTERI, OF NEW YORK, N. Y.

NON-REFILLABLE BOTTLE.

1,112,067.

Specification of Letters Patent. Patented Sept. 29, 1914.

Application filed March 12, 1914. Serial No. 824,095.

To all whom it may concern:

Be it known that we, GAETANO IMPELLITTERI, a citizen of the United States, and ANTONINO IMPELLITTERI, a subject of the 5 King of Italy, both residing in the city, county, and State of New York, have invented certain new and useful Improvements in Non-Refillable Bottles, of which the following is a full, clear, and complete disclosure.

Our invention relates to a self-acting closure for bottles of the so-called non-refillable type, and contemplates a device consisting of few, inexpensive parts, easy to 15 make and assemble, and adapted and arranged to close the bottle opening before the bottle reaches a horizontal from an inverted position.

The advantages and utility of our invention will be understood readily from the 20 following description.

Referring to the drawings accompanying and forming a part of this specification, wherein we have illustrated one embodiment of our invention,—Figure 1 is a vertical section showing parts in elevation; Fig. 2 a section similar to Fig. 1 but showing the bottle inverted; Fig. 3 a section similar to Fig. 1 but showing the bottle halfway between an inverted and a horizontal position; Fig. 4 a section similar to Fig. 1 but showing a modification; and Fig. 5 an elevation of the parts forming our closure showing them spaced apart for clearness of illustration.

Similar reference characters refer to similar parts throughout the drawings.

Reference numeral 1 indicates a bottle of ordinary form and proportions having a 40 neck 2 and sloping or curved shoulders 3. The point of curvature between the neck and shoulders is indicated at 4.

Resting on the top of the bottle is a cap 5, preferably of the same outside dimensions 45 as the top of the bottle on which it rests and having side walls of less thickness than said bottle top. The top portion of the cap is provided with an opening 6 of less diameter than the diameter of the bottle opening 50 in order to form a horizontal shoulder 8 for a purpose to be described hereinafter. The cap is secured on the bottle by a metal band 9 spun or crimped around the cap and bottle, or by any other desired fastening means.

Also resting on the top of the bottle, 55 within the cap 5, is a hollow valve chamber

10 open at the bottom (Fig. 1), and provided with side openings 13. Side spacing members 14 having upward extensions 15 (Fig. 4) are formed on the outside of the 60 valve chamber to space the side walls of the chamber from the inside of the cap, and to space the top of the valve chamber from the horizontal shoulders 8 near the top of the cap. It is obvious that the valve chamber and cap may be formed in one piece if desired.

Resting on the inner edge of the bottle opening is a valve member consisting of an inverted semi-cylindrical portion 16 and an extension or stem 17. The upper surface of the portion 16 is recessed or cupped as shown at 18 in order to reduce its weight and prevent any possibility of its sticking to the horizontal shoulder 8. The inner edge 70 of the bottle opening may be beveled, if desired, to form a seat for the valve member. On the stem 17 is mounted a radially recessed spacing member 20, and at the bottom of the stem is secured a weight 21, preferably 80 by a flexible cord as indicated at 22.

The operation of the device is as follows: When the bottle is in vertical position as shown in Fig. 1, it is impossible to introduce liquid into the bottle as the valve member 85 tightly closes the bottle opening. When the bottle is inverted the parts assume the position shown in Fig. 2. The liquid flows around the weight 21, through the radial recesses or openings of spacing member 20, 90 into the valve chamber 10, out through side openings 13, between the side of the chamber and the side of the cap, then between the top of the chamber and shoulder 8, and thence out through the opening 6. The 95 parts are so proportioned that when the bottle is in inverted position (Fig. 2) the weight 21 rests on the end of stem 17, and on the side of the bottle approximately at its point of curvature 4 so that if a line, as $a-a$, be drawn through the point of contact of the weight with the bottle and at right angles to the neck of the bottle, the center of gravity of the weight will be on the other side of said line from the end of the stem. By reference to Fig. 3, it will be seen that by means of this construction, the weight will fall down the inclined or curved shoulder 3 before the bottle can be turned to horizontal position or even to thirty degrees from perpendicular, thereby closing the valve and preventing the entrance of any liquid into 100 105 110

the bottle. This prevents the introduction of liquid into the bottle by the well-known method of pouring liquid into the top when the bottle is in an upright position, closing the top opening, and bringing the bottle so slowly and carefully to a horizontal position that the valve will not close. It is impossible to refill the bottle by this method with our closure as the valve closes positively before the bottle reaches a horizontal position. If an attempt be made to refill the bottle by shaking, the weight is liable to break the bottle. It also is impossible to refill the bottle by creating a partial vacuum. The valve will not lift entirely from its seat but will only tilt or rock to a very slight degree.

If it is desired to provide a small and light valve member with a large and heavy weight, a washer 7 may be utilized as shown in Fig. 4, adapted to fit the top of the bottle. The valve thus can be made considerably smaller than the bottle opening and consequently lighter. The ball member is not limited in size by the opening in the washer but may be as large as the bottle opening and consequently heavier. It is obvious that the principle of operation is not modified by the use of said washer and that the claims are to be construed accordingly.

Having described one embodiment of our invention, which we understand may be modified without departing from the principle thereof or from the scope of the claims, what we claim is:

1. A combination in a non-refillable bottle of a bottle and means to prevent the

flow of liquid in one direction comprising a cap, a valve chamber adapted to rest on the top of said bottle, means to space said chamber from said cap at its top and sides, a valve adapted to rest on the top of said bottle and movable within said chamber, a valve stem, means to space said stem from the sides of said bottle, and a weight secured to the stem by flexible connection adapted when the bottle is inverted to rest on the end of said stem and on the side of the bottle approximately at the point of curvature between the neck and body of the bottle, substantially as described.

2. The combination in a non-refillable bottle, of a bottle, and means to prevent the flow of liquid in one direction comprising a cap, a valve chamber adapted to rest on the top of said bottle, a valve adapted to rest on the top of said bottle and movable within said chamber and provided with a stem, and a weight secured to the stem by a flexible connection adapted to rest on the end of said stem and the sides of said bottle when said bottle is inverted and so arranged that if a line be drawn through the point of contact of said weight with said bottle at right angles to the side of the neck of said bottle the center of gravity of said weight will be on the opposite side of said line from said stem.

GAETANO IMPELLITTERI.
ANTONINO IMPELLITTERI.
